T. H. McCREA,
CONSTRUCTION OF WALLS,
APPLICATION FILED MAY 2, 1916.

1,330,203.

Patented Feb. 10, 1920.

Inventor:
Thomas H. McCrea,

Attys.

UNITED STATES PATENT OFFICE.

THOMAS H. McCREA, OF BRAZIL, INDIANA, ASSIGNOR TO BRAZIL HOLLOW BRICK & TILE COMPANY, OF BRAZIL, INDIANA, A CORPORATION OF INDIANA.

CONSTRUCTION OF WALLS.

1,330,203.

Specification of Letters Patent. Patented Feb. 10, 1920.

Application filed May 2, 1816. Serial No. 94,884.

To all whom it may concern:

Be it known that I, THOMAS H. McCREA, a citizen of the United States, and a resident of Brazil, county of Clay, and State of Indiana, have invented an Improvement in the Construction of Walls, of which the following description, in connection with the accompanying drawings, is a specification, like characters on the drawings representing like parts.

This invention relates to the construction of walls and the purpose is to provide an improved type of wall, and an improved material from which such a wall may be formed.

A particular object of my invention is to provide a wall construction which shall be fluid proof and which may be advantageously used in building fluid containers such as reservoirs, silos, etc., although its utility is by no means limited to such containers. My invention will be best understood by reference to the following description taken in connection with the accompanying drawings, wherein:

Figure 1 is a perspective view of a building unit constructed according to my invention;

Fig. 2 is a perspective view partially broken away of a portion of wall built in accordance with my invention with units such as are shown in Fig. 1; and

Fig. 3 is a section on the line 3—3 of Fig. 2.

In the embodiment of my invention which I have chosen for illustration, the unit from which a wall may be constructed is shown as similar to the units now known as hollow tiles. For convenience in description I shall hereafter refer to each unit as a tile although it will be understood that I do not imply thereby that my invention is limited to the vitreous plastic to which the name tile is ordinarily given. In Fig. 1, one tile is shown in perspective and it is there shown as curved longitudinally so as to adapt it for building a wall curved circularly or otherwise. In the illustrative embodiment the tile comprises the front and back walls 1 and 2 joined by the upper and lower sides 3 and 4 and the central web 5. The two sides 3 and 4 and the web 5 define two passages 6 and 7 extending longitudinally through the tile. The top and bottom sides 3 and 4 are preferably channeled longitudi-

nally as shown at 8 and 9 and desirably these channels are undercut or dove-tailed.

Either the front wall 1 or the back wall 2 of the tile or, as shown, both of them also has longitudinal passages therethrough and I have here shown three passages 10, 11 and 12 in each wall. The uppermost passage 10 is preferably of such dimension that it extends upwardly at least to and preferably beyond the bottom of the channel 8 in the upper face 3 of the tile and extends downwardly at least to and preferably beyond the level of the upper part of the passage 6. The next lower passage 11 is disposed opposite the joining web 5 and preferably extends beyond the faces of that web on each side so that it laps both passages 6 and 7. The lowermost passage 12 is disposed as regards the passage 7 and the channel 9 in the same way as is the passage 10 as regards the passage 6 and the channel 8. In other words, the two passages 6 and 7 are staggered with respect to the three passages 10, 11 and 12 in the wall of the tile and the channels 8 and 9, which may be considered similar passages which open laterally to the sides of the tile, are similarly staggered. I prefer that the passages of the two staggered sets should overlap on each other as shown.

A number of tiles such as shown in Fig. 1 are adapted to be used in the formation of a wall by being set in any suitable cementitious connective 13 such as cement or mortar in a manner which will be well understood. I find it desirable to reinforce this connective by means of suitable reinforcing rods 14 as shown in Fig. 2. The connective 13 when placed between adjacent side faces of the blocks will enter and fill the oppositely disposed dove-tailed channels 8 and 9 as shown in Fig. 2 and form an interlocking joint with the same. Where it intervenes between the adjacent ends of the tiles it will enter the ends of the various passages to some extent and form there an interlocking joint as shown in section by Fig. 3. In other words, the passages, which in the embodiment shown extend entirely through the tile, present recesses at each end thereof, which are adapted to receive the cement or similar connective and form an interlocking joint. As will be seen by an inspection of Fig. 3, the joint between the connective 13 and the tile is in the na-

ture of a mortise and tenon joint and in the particular case chosen for illustration the mortises are provided by the open ends of the various passages in the tile and the tenons are formed by the plastic cement which flows into them.

By this construction of wall wherein the interstices between the various units form what I have here called a mortise and a tenon joint and which is exemplified by the interengagement of the connecting cement with the ends of the passages, a thoroughly weather-proof and fluid-proof structure is provided for. The materials of which the wall is composed, that is, the tiles themselves and the cement as such, are practically impervious but when a wall is built up from units it is possible for fluid to seep through the joints and thus enter the interior of the structure. By the construction of tile such as I have described, this seeping is minimized. Referring to Fig. 2, it will be seen that if water starts to work through the wall at the horizontal joint between the tile and the cement, it will encounter the dove-tailed rib caused by the entry of the cement 13 into the channel 9 and will be checked. In other words, to permit a leakage through this horizontal joint the water must follow in a circuitous and tortuous course along the joint 15 then up and across the dove-tail 16 and down on the other side thereof and through the joint 17. Such a movement of water is practically impossible. With reference now to the joint between the ends of the tiles, that is, the joint which is vertical in Fig. 2 and which is shown in section in Fig. 3, it will be seen that the water entering at the joint 18 must again follow a circuitous course about and over three ribs or tenons formed by the connective which has entered the recesses or mortises formed by the ends of the various passages in the tile. If the water were permitted to enter at about the location of the section line 3-3 it is obvious that it would have to pass about three of these obstructions. It is probable, therefore, that the water which came into contact with the tenon entering the passage 10 would seek to find a way through between the two passages 10 and 11. Because of the staggered construction of tile which has been described, it would then encounter the tenon formed by the cement entering the passage 6. If it seeped down from here to the web 5 it would then come into contact with the tenon formed in the inner passage 11. It is, however, practically impossible that the leakage would have progressed so far and the above course is traced out simply to show how the construction which has been described provides for presenting in all directions a tortuous course to moisture. The passages 10 obstruct the space between the base of the

channel 8 and the top of the passage 6. The passage 11 obstructs the space between the two passages 6 and 7 formed by the web 5, and the passage 12 the space between the bottom of passage 7 and the top of channel 9. Similarly the two passages 6 and 7 provide for guarding against the entrance of any water in the spaces between the passages 10, 11 and 12. In other words, no matter how a transverse line may be passed through the joint, it will intersect one or more of the tenons which are formed by the entrance of the cementitious connective into the ends of the tile.

For clearness in the above description I have referred to the various parts of the building unit or tile by such words as "top", "bottom" and the like. Obviously, however, these words are not to be taken as having a limiting effect as the disposition of the unit is immaterial. I have furthermore described the single illustrative embodiment shown in considerable detail in order that the principles of my invention might be most clearly understood and have used specific words in so doing, but it will be understood that I have done this with a descriptive rather than with a defining purpose and that the particular features so fully described are illustrative merely.

What I do claim and desire to secure by Letters Patent is:

1. A building unit for wall construction comprising a hollow tile having side walls connected by cross webs to afford longitudinal dead air spaces, said side walls extending beyond an outer cross web to provide a recessed mortar bed and containing a plurality of narrow, open-ended mortar-keying air spaces opposite the respective cross webs and substantially overlapping said dead air spaces, those of said narrow air spaces contiguous to said mortar bed extending at least to the bottom thereof, substantially as and for the purpose described.

2. A wall comprising a plurality of tiles in superposed rows, having a mortar filling between adjacent surfaces of the tiles, said tiles comprising side walls connected by spaced cross webs affording longitudinal dead air spaces, there being longitudinal mortar engaging recesses between corresponding horizontal surfaces of adjacent tiles, said side walls having a plurality of open-ended mortar-keying air spaces staggered relative to and substantially overlapping said dead air spaces, certain of said last mentioned air spaces reaching at least to the said mortar beds.

In testimony whereof, I have signed my name to this specification.

THOMAS H. McCREA.
